Attorneys.

UNITED STATES PATENT OFFICE.

JOHN H. GRAYSON, OF ATHENS, OHIO.

DESIGN FOR A GAS-HEATER.

59,839.

Specification for Design.

Patented Nov. 29, 1921.

Application filed January 3, 1921. Serial No. 434,817. Term of patent 14 years.

To all whom it may concern:

Be it known that I, JOHN H. GRAYSON, a citizen of the United States, residing at Athens, in the county of Athens and State of Ohio, have invented a new, original, and ornamental Design for Gas-Heaters, of which the following is a specification, reference being had to the accompanying

drawing, forming part thereof, and wherein:

Figure 1 is a front view of the heater, and Fig. 2 is a side view of the heater.

I claim:

The ornamental design for a gas heater, as shown.

JOHN H. GRAYSON.
